W. WILBURGER.
ALBUM FOR DISK RECORDS.
FILED SEPT. 21, 1921.

75 Inventor
William Wilburges

By
Frederick V. Thaxter,
Attorney.

UNITED STATES PATENT OFFICE.

WILLIAM WILBURGER, OF BROOKLYN, NEW YORK.

ALBUM FOR DISK RECORDS.

Application filed September 21, 1921. Serial No. 502,227.

To all whom it may concern:

Be it known that I, WILLIAM WILBURGER, a citizen of the United States, and resident of Brooklyn, in the county of Kings and State of New York, have invented certain new and useful Improvements in Albums for Disk Records, of which the following is a full, clear, and exact specification.

This invention relates to albums for holding disk records for phonographs or talking machines, or for other purposes, and has for its object to provide an improved binding or holding means for the pocketed leaves which will increase the capacity of the albums without enlarging their outside widths.

Another object is to strengthen these albums and to render the binding channels thereof less liable to injury and cracking when in use. Other objects will appear as the description proceeds.

The invention will be first hereinafter described in connection with the accompanying drawings, wherein similar reference characters are used to designate corresponding parts throughout the several views, and the details of the invention then defined more particularly in the claims at the end of the description.

In the drawings:—

Figure 1 is a plan view of an album constructed substantially in accordance with this invention, the front cover being shown in open position, and

Figure 2 is a sectional view of the closed album taken transversely thereof in line with one of the leaf-holding bars, the parts being drawn to a larger scale than in Figure 1 and the free end portions of the leaves and covers being broken away.

The rigid channeled binding member 1 of the album is made of metal formed with the curved base portion 2 and parallel outstanding flanges 3 projecting a suitable distance at the lateral edges of said base portion between the covers 4. The base portion 2 of the channel member is preferably overlaid with the usual cushion layer 5, see Figure 2, and the covers 4 are hinged to the lateral edge portions of said member by textile coverings 6 and 7 glued or otherwise secured to the inner and outer faces of the base portion 2 and corresponding faces of the cores 8 of said covers 4.

The inner textile covering 7 conforms to the interior contour of the channel member

1, including its base portion 2 and flanges 3, and also covers the outer edges and outer faces of said flanges, as clearly shown in Figure 2, while the outer textile covering 6 60 conforms to the outer surface of the cushion layer 5. The hinges for the covers 4 of the album are formed by loose portions of the textile coverings 6 and 7 between the cores 8 of said covers and the lateral portions of 65 the channel member 1 at the bases of the flanges 3, as indicated at 9 in Figure 2.

The pocketed leaves 10 have eyelets 11 loosely fitted on cross bars 12 extending between the flanges 3 of the channel member 1. 70 Said cross bars are preferably made in such a way as to be removable from the channel member in order to permit the leaves to be changed or replaced when desired. For this purpose, each cross bar may be made with 75 a head 13 at one end integral with the shank 14 thereof, while its other end may be formed with an axial socket to detachably receive a pin or lug 15 having a head 16 to engage one of the flanges 3, the head 13 80 engaging the other flange, as shown in Figure 2. Any other means for detachably securing the leaves in the channel member 1 between the flanges 3 may be used, however, without departing from this invention. 85

It will be noted that the metal channel member herein shown and described is more durable than the wooden channels heretofore used in albums of this kind, there being no danger of said metal member breaking or 90 cracking under abnormal treatment as was the case with the wooden channels. Moreover, by using the metal channel of the present invention, the width of the interior of the channel is considerably increased over 95 that of a wooden channel having the same outside dimension, so that the storage capacity of the album is increased, it being possible to insert a greater number of leaves in said metal channel than in said wooden channel, 100 as will be readily understood.

The flanges 3 are preferably inset from the lateral edges 17 of the channeled member forming steps 18 on the outsides of said flanges, as clearly shown in Figure 2, and 105 the hinged edges of the covers 4 lie in said steps where they are substantially flush with said lateral edges 17 of the channeled member when the covers are closed. Said edges of the covers are thus protected from being 110 crushed when a number of albums are wedged together on a shelf, the pressure of

strain being taken by the protruding lateral edges 17 of the rigid metal channeled member.

I claim:—

- 5 1. In an album of the character described, the combination with a channeled back member having marginal flanges, of covers, flexible strips secured over the outer and inner faces of said channeled member and to the outer and inner faces of said covers for hinging the latter to the former, said inner flexible strip being folded over the flanges of the channeled member so as to cover both faces thereof as well as their edges, and
- 10 15 means for fastening leaves in said channeled member between said flanges.
2. In an album of the character described, the combination with a channeled back mem-

ber having marginal flanges inset from the lateral edges thereof forming steps on the 20 outsides of said flanges, of covers, flexible strips secured over the outer and inner faces of said channeled member and to the outer and inner faces of said covers for hinging the latter to the former, said covers lying 25 in said steps on the outsides of the flanges substantially flush with the lateral edges of said back member when the covers are closed, said inner flexible strip being folded over the flanges so as to cover both faces and 30 the edges thereof, and means for fastening leaves in said channeled member between said flanges.

In testimony whereof I have signed my name to this specification.

WILLIAM WILBURGER.
